COMBINED END TABLE AND LAMP

Hiawatha R. Hawkes, 4001 Don Diablo Drive,
Los Angeles 8, Calif.

Substituted for abandoned design application Ser. No.
64,225, Mar. 1, 1961. This application July 17, 1963,
Ser. No. 75,942

Term of patent 14 years

(Cl. D33—14)

I claim:

The ornamental design for a combined end table and lamp, as shown and described.
